UNITED STATES PATENT OFFICE.

CHARLES O. BRUNO, OF ROCKFORD, ILLINOIS.

DEVICE FOR ASSEMBLING BROOD-FRAMES.

1,274,240.

Specification of Letters Patent. Patented July 30, 1918.

Application filed April 23, 1917. Serial No. 164,040.

To all whom it may concern:

Be it known that I, CHARLES O. BRUNO, a citizen of the United States, residing at Rockford, in the county of Winnebago and

5 State of Illinois, have invented certain new and useful Improvements in Devices for Assembling Brood-Frames, of which the following is a specification.

This invention relates in general to the 10 art of bee culture, and has more particular reference to an appliance employed in the assembly of brood frames. Brood frames, as they are popularly known and well understood in the art serve to hold the comb 15 foundations or comb starters in the brood chamber of a beehive and by long usage have become practically standardized in construction so as to comprise side bars connected by a top and a bottom bar. The

20 comb foundation composed of bees wax is secured in a groove in the top bar through the agency of a long narrow wedge and is further secured to the frame by thin wiring traversed back and forth over and embedded in the foundation and being secured to the side bars. These brood frames, the 25 apiarist purchases in knock-down form, the parts for one frame consisting of a pair of side bars, a top and a bottom bar, all of

30 which are of wood, a bees wax comb foundation, and a long narrow wood wedge for securing the comb foundation to the top bar. The top bar is double grooved on its underside so that one groove receives the 35 comb foundation and the other the wedge, the latter being employed to press the narrow wood portion intermediate the grooves into the bees wax and thereby secure the same to the top bar.

40 It is now common practice for the apiarist to assemble these parts by hand, nailing the side bars to the top bar, then nailing the bottom bar to the side bars, thence inserting the comb foundation and wiring the 45 frame and inserting the wedge to secure the comb foundation in position in the frame, and finally, in placing a staple in each top end of the brood frame so as to serve as end stops coöperable with the main

50 brood chamber frame for properly spacing the brood frame therein. Because of the various operations thus required for assembling a brood frame and because of the considerable number of these frames necessary for equipping a number of hives, considerable time and labor must be expended

in assembling operations, and in many instances, because of the hand methods employed, the frames are not assembled with the uniformity and accuracy desired.

60

The primary object, therefore, of my invention is to provide a new and useful appliance for assembling brood frames of the character described so that they may be expeditiously and accurately assembled at a 65 much lower cost than has heretofore been found possible.

I have also aimed to provide an appliance of this character which shall be of 70 very simple and inexpensive construction so that it will serve the purpose for which it is designed in a practical manner and may be produced as an article of manufacture at a comparatively low cost.

In furtherance of these general objects I 75 have provided an appliance of novel construction embodying various advantageous features, all of which may be fully understood and appreciated by those skilled in the art by reference to the following description when considered in connection with the accompanying drawings, in 80 which—

Figure 1 is a plan view of an appliance embodying my improvements, showing the 85 parts in the position assumed for the first operation of nailing the side bars to the top bar and showing in dotted lines the manner of wiring the frame;

Fig. 2 is a fragmentary perspective view. 90 illustrating the nail-driving device; and

Figs. 3 and 4 are fragmentary perspective views showing corners of the brood frame, the illustration in Fig. 4 showing the side bar removed.

95

A brood frame such as is adapted to be assembled by means of my novel appliance, consists of side bars 8 and 9, top and bottom bars 11 and 12 respectively, a bees wax comb foundation or comb starter 13 and a 100 wedge 14 and wiring 15 for securing the comb foundation to the side and top bars. As shown in Fig. 3, the side bars are recessed at their ends to receive the reduced ends 16 of the top and bottom bars. In assembling 105 these parts each side bar 8 is secured to an end of the top bar by means of two nails 17, shown in Fig. 3, and a staple 18 is applied to each side bar in the manner shown to serve as a stop for holding the brood 110 frame in proper position in the brood chamber of a bee hive. Instead of placing the

staple 18 centrally between the edges of the side bar and, therefore, directly opposite the comb foundation, it is desired to insert the staple on that side of the comb foundation opposite to the wedge, so that the staple will enter a solid body of the top bar, as indicated in Fig. 4.

Referring now to my novel appliance, it will be noted that a main frame or base of 10 rectangular shape designated generally by reference character 19 is provided and carries the several parts and devices employed in the course of assembling a brood frame. A table 21, as it were, is mounted on the 15 base 19 for supporting the comb foundation when the brood frame is being wired, the edges of the table serving as guides or gages for determining the position of the top bars and side bars during the assembling operation. Thus the edge 22 of the table, together with the face 23 of a block 24, constitute sides of a channel guide in which the 20 top bar may be placed and held in position on the frame. The edges 25 and 26 of the 25 table serve as gages or stops with which the side bars coöperate when the brood frame is laid flat on the base as indicated in dotted lines in Fig. 1 during operations other than 30 nailing the brood frame. A stop 27 in alinement with the channel formed by the faces 22 and 23 and the base, limits movement of the top longitudinally in one direction when 35 said bar is seated in the channel and thereby determines the operative assembling position of the said top bar.

Since the first operation in assembling the brood frame is to nail the side bars to the top bar, the latter (which contains on its underside a pair of parallel grooves 28 and 40 29 for the reception of a wedge and a comb foundation, respectively) is placed grooved side up in said channel on the frame and in contact with stop 27, as shown in Fig. 1, and the side bar 9 is positioned, as shown, in co- 45 operative engagement with the top bar ready to be nailed thereto. A nailing device is now provided for applying the nails 17 to thereby secure the side bar 9 to the top bar. This nailing device, positioned on the base 50 in longitudinal alinement with the top bar, consists of a driving element or plunger 31 slidably mounted in a suitable casing 32 secured to the base and adapted to be moved lengthwise toward the side bar 9 by means 55 of a pivoted cam lever 33 operable by the hand of an operator as will be obvious, against the pressure of an expansion spring 34 confined in the housing 32 below the plunger 31 and in engagement with a lug 35 60 depending from said plunger. This spring serves to automatically return the nail driver and its operating lever to inoperative position after the nails have been driven. Means is disposed intermediate the nail driver and 65 the adjacent end of the top bar for properly

positioning a pair of nails intermediate the plunger and side bar so that the plunger may engage the nails and drive them as desired. This means, best shown in Fig. 2, consists of a plate 36 yieldingly and depressingly 70 supported at its ends on springs 37, which are coiled about screws or posts 38 passing through the plate 36, the latter being grooved on its upper face providing a pair of seats 39 for the reception of nails and being cut 75 away intermediate said seats to provide a staple gage having faces 41 and 42. Thus a combined nail and staple positioning means is provided by means of which, in connection with the driving device, the nails and 80 staples may be quickly and accurately applied. It will be noted that the top of the blade is disposed in the path of the plunger and that the nail seats 39 are deeper at their ends adjacent to the plunger than at their 85 forward ends; also that the plunger is provided with nail head seats 43 which may be of any suitable form. The operator places two nails in the seats 39 with the heads at the deepest portions thereof and the points 90 projecting beyond the plate 36 into close proximity to the side bar 9 and then advances the plunger 31 with one hand through the agency of the lever 33 so as to press the nails forwardly and with the other 95 properly enters the points of the nails into the side bar. After the plunger is advanced to drive the nails the forward under edge of the plunger which is slightly beveled will engage the top of the plate 36 and depress 100 the same to thereby withdraw it from the nails and not interfere with the heads thereof. Thus the nail positioning means is depressed by the plunger when driving the 105 nails and passes entirely over said means. 110 The nails 17 are thereby applied and will pierce the top bar on both sides of its grooved portion, as indicated in Figs. 3 and 4. When the operator releases the handle 33 the spring 34 will retract the plunger and 115 the nail positioning means will be automatically raised to operative position. The operator will then remove the top bar and re-position it in the channel with the side 120 bar 9 adjacent to the stop 27 so that the side 115 bar 8 may be secured to the top bar by means of the nailing device in the manner just described. A staple 18 may be, however, applied to the side bar 9 immediately after 125 nailing the same, and in the same manner following the nailing of the side bar 8. In the position which the top bar assumes when the side bar 9 is being applied the widest portion of the top bar on its grooved side is located adjacent to the face 42 of the staple 125 gage, and therefore, a staple will be placed on edge, resting on the extension 16 of the top bar and against the face 42, and will be pressed into the side bar at one side of the 130 comb foundation groove 29 by operation of

the plunger. When the side bar 8 is to be stapled, the staple will be positioned against the face 41 and applied in the manner indicated in Figs. 3 and 4.

5 While the parts are in this position, that is, with the side bars projecting upwardly the bottom bar 12 may be inserted in the cutaways in the now uppermost ends of the side bars and nailed thereto by hand as this 10 operation may be very easily and simply performed without moving the parts from the base.

15 The wiring of the brood frame by wire 15 from the spool 4 and the securing of the comb foundation 13 to the frame through the means of the wedge 14, which is adapted to be forced into position by operation of the cam levers 53 carried by the pivoted frame sections 47 are not claimed in this application as they constitute independent 20 subject matter.

25 By means of an appliance embodying the novel features just described, it will be evident that brood frames may be accurately and expediently assembled and that the several operations performed are all done in a very practical and efficient manner. It

should be understood that while I have shown and described one practical embodiment of my improvements, various changes 30 and modifications might be made in the construction without departing from the spirit and scope of the invention as expressed in the appended claim.

I claim:

In a device of the character described for assembling brood frames, a frame for supporting the brood-frame parts, a nail driving device on said frame including a nail driving element, a nail supporting and positioning means interposed between the nail driving element and the work comprising a horizontally disposed member having spaced nail-receiving grooves in its upper surface whereby a plurality of nails may be supported in a horizontal position intermediate and in alignment with the nail-driving element and the work, and means yieldingly supporting the nail carrying member at each end thereof so that said member may be yieldingly depressed when the nail driver is operated to drive the nails.

CHARLES O. BRUNO.
